UNITED STATES PATENT OFFICE.

JAMES C. ANDERSON, OF JERSEY CITY, NEW JERSEY.

MEANS FOR COOLING AUTOMOBILE-ENGINES.

SPECIFICATION forming part of Letters Patent No. 763,949, dated July 5, 1904.

Application filed January 21, 1904. Serial No. 189,963. (No model.)

To all whom it may concern:

Be it known that I, JAMES C. ANDERSON, a citizen of the United States, residing at Jersey City, in the county of Hudson and State of New Jersey, have invented certain new and useful Improvements in Means for Cooling Automobile-Engines, of which the following is a full, clear, and exact description.

This invention relates to means for cooling explosion-engines, and has special reference to the cooling of such engines when used upon automobiles.

The disadvantages connected with water-cooled engines are well known, prominent among which may be mentioned the liability of the water to freeze in cold weather, the complexity and weight of the various pipes, tanks, and pumps in the circulatory system, and the care required to keep the apparatus in good working order. To avoid these disadvantages, attempts have been made to cool the engine by circulating air around the cylinders and valve-boxes, this being accomplished by means of fans driven by the engine and also by the draft created by the movement of the vehicle when the engine is used to drive an automobile. Air-cooled engines are, however, not considered to be so effective as the water-cooled engine, the principal difficulty residing in the fact that air cannot be passed rapidly enough around the engine to keep it at an efficient working temperature. Any arrangement, therefore, in air-cooled engines which will circulate the air most rapidly in contact with the walls of the engine or which will bring the coolest available air into contact therewith will be an advantage. These things I have accomplished by my invention, as will appear from the description herein-after. It should first be pointed out, however, that an accepted construction for automobiles driven by a multiplex-cylinder engine is one in which the engine is placed under a hood at the forward end of the car with the cylinders arranged in a fore-and-aft line, so that the crank-shaft will be at right angles to the axles and permit of the simplest and most effective form of power transmission between said crank-shaft and the axle. An engine arranged with its cylinders one behind the

other in this manner, however, is not in the most advantageous position to be cooled by the circulation of air due to the motion of the vehicle, for the reason that an unequal cooling results, because the air first impinges against the front cylinder and is to an extent heated, so that it is not so effective on the cylinders behind. For this reason it has heretofore been proposed to turn the engine around, so that its shaft is parallel to the axles and the cylinders arranged abreast across the front of the vehicle. This results in a uniform cooling by air, but introduces difficulty in the transmission of power from the engine to the rear axle and limits the size and power of the engine to the available width of the vehicle-frame.

A feature of my invention is to provide for the cooling by air of a multiplex-cylinder engine in which the cylinders are arranged in the fore-and-aft or most approved position and by such means that the air at atmospheric temperature will strike all of the cylinders at the same time and will have the same cooling effect thereon as if they were placed abreast across the front of the vehicle.

Another disadvantage in the cooling of the engine entirely by a blast of air created by the movement of the vehicle itself is the fact that when the engine is running at high speed and the vehicle is either stationary or running at low speed the quantity of air passing the engine, which under such circumstances should be the greatest possible, is, in fact, none in case the vehicle is standing still and comparatively little in case it is moving at slow speed.

It is therefore another object of my invention to provide means for maintaining a movement of air past the engine at speed proportionate to the speed of the engine, so that whether the vehicle be stationary or running the movement of the air will not vary. My construction, however, is such that I am able to take advantage of the motion of the vehicle to help produce the necessary cooling-current of air.

The invention will be described in detail with reference to the accompanying drawings, in which—

Figure 1 is a horizontal section through the hood at the front of an automobile, showing a portion of the machinery in plan. Fig. 2 is a vertical section of the hood on line $x-x$ of Fig. 1, showing the machinery in side elevation. Fig. 3 is a transverse section of the hood, showing the engine in end elevation; and Fig. 4 is a sectional detail of the exhaust-nozzle and air-passage.

10 A is a portion of the flooring of the body of an automobile, B the dashboard, and C the hood covering and protecting the engine and located in front of the dash.

E is the engine, shown as having four cylinders arranged in a plane running fore and aft of the car, the crank-shaft e being at right angles to the axles of the vehicle. The space inclosed by the hood and occupied by the engine is divided into two compartments by a 15 partition f , running fore and aft and occupying a plane substantially coincident with the vertical axes of the cylinders, the partition having an opening fitting closely over the cylinders. The forward end of the partition 20 along the vertical line where it abuts against the forward cylinder is deflected and leads thence in a diagonal direction, as indicated by the part f' , to one corner of the front of the hood, and the front of the hood being open, 25 as usual, air passing therethrough will have access only to one of the compartments into which the hood is divided. This compartment is by design the one in which the valve-chambers e^* of the various cylinders of the 30 engine are located. The front of the hood is a grill or lattice work d , made up of vertical blades set at an angle to the direction of motion, such that air passing between them will be deflected toward the compartment containing the valve-boxes. This compartment, 35 for the sake of clearness, I will designate as g , and the other compartment as g' . The engine is provided with the usual thin flanges or wings e' on its exterior walls to furnish 40 large contact-surface for the air to facilitate the exchange of the heat. These flanges are placed around the upper ends of the cylinders and the valve-boxes where the greatest heat is generated, and the spaces between them form 45 free passages of communication from the compartment g to the compartment g' , the zone below the flanges being closed by the partition f . From the chamber g' an exhaust-tube h of considerable diameter leads toward the rear 50 of the vehicle, and in this tube is placed the exhaust-nozzle i of the engine. This exhaust-nozzle consists of a hollow ring having an annular opening i' presented toward the exit of the tube, the ring being axially located in the 55 tube. At the point where the ring opens into the tube there is an annular restriction or throat j , formed by the casting j' . The object of this construction is to afford large contact of the escaping products of combustion with the 60 column of air, so as to transfer a maximum of 65

propulsive effect to the latter and also to obtain a rapid and thorough interchange of heat between the two named gases, all of which better utilizes the available energy of the products of combustion and contributes to a 70 silent exhaust or exit. The exhaust-pipe k from each cylinder leads to a trunk-pipe l , which in turn leads to the ring or nozzle i . Thus the exhaust from all of the cylinders passes through this nozzle.

75 The operation is as follows: While the vehicle is in motion a current of air is caused to pass through the open front of the hood and be deflected into the compartment g , from which it passes simultaneously into contact 80 with the exterior walls of all of the cylinders. It is forced through the many spaces between the flanges of the cylinders into the compartment g' . It then finds an exit through the tube h , past the exhaust-nozzle i , and again to the 85 atmosphere through the rear end of the tube. It will thus be seen that by dividing the hood into the two compartments located on opposite sides of the engine the air at atmospheric temperature strikes the valve-boxes and walls 90 of the various cylinders all at the same time, as if, in fact, the engine was arranged with its cylinders abreast across the front of the machine. One cylinder is therefore cooled to the same extent as the others. Besides the 95 current of air produced by the movement of the vehicle a current more to be relied upon will be produced by the running of the engine. Since the exhaust-passages from the cylinders all lead to the nozzle i , a suction will be produced in the tube h in the direction of its exit to an extent depending upon the speed of the engine or the pressure of its exhaust. This suction will draw air from the compartment g into the compartment g' and force it outward through the end of the tube h . Thus if the engine is running free and the vehicle stationary a circulation of air to cool the engine will still be maintained. Also if the vehicle is running uphill with its engine running at 100 high speed and the vehicle at low speed, owing to the low ratio of gear connection, there will still be an adequate circulation of air to accomplish the necessary cooling. I am aware that in some air-cooled engines the current of 105 air is created partially by fans driven by the engine, which in so far as their utility to cool the engine while the vehicle is stationary is concerned is the equivalent of my invention; but from the standpoint of simplicity of apparatus and operation I consider my method of utilizing the exhaust to be superior. There is always more or less power wasted in the 110 exhaust from these engines, and by properly designing the nozzle i and the passage h this power can be utilized without objectionable reaction. In fact, the nozzle and the tube can be incorporated into a muffler, in which case 115 they will add substantially nothing to the cost of the outfit. I propose placing a door in 120

125

130

135

the side of the hood, as shown at *o*, opening into the compartment *g*, which will give access to all parts of the engine requiring attention, and same may be opened for the purpose of 5 making adjustments of the engine while it is running without in any way interfering with the cooling of the engine, according to the plan of the engine.

It will thus be seen that in an air-cooled 10 engine I have preserved the present accepted type of machine and at the same time provided means for cooling the cylinders uniformly and for applying the cooling agent in accordance with the speed of the engine 15 without relying upon the speed of the vehicle.

It is observed that the arrangement of chamber *g* at one side of the engine and the provision for conducting air into it and then into contact with the external walls of the engine 20 will perform a useful function without the chamber *g'* as such on the opposite side. This latter chamber is provided mainly to allow the suction of the exhaust to act upon the air cooling-column.

25 Having described my invention, I claim—
1. In an automobile, a multicylinder-engine arranged with its cylinders in a fore-and-aft line, a casing covering the engine, said casing having an opening for air, an air-passage 30 leading from said opening to one side of the engine and an exit for air on the opposite side of the engine.

2. In an automobile, a multicylinder-engine arranged with its cylinders in a fore-and-aft line, a casing covering the engine, a partition 35 in the casing dividing it into two compart-

ments, an entrance for air in one compartment and an exit for air in the other compartment, said partition having an opening through which air can pass from one compartment to 40 the other, the engine being located in a position to be struck by the air on its way from one compartment to the other.

3. In an automobile, a multicylinder-engine 45 arranged with its cylinders in a fore-and-aft line, a casing covering the engine, a partition in the casing dividing it into two compartments, an entrance for air in one compartment and an exit for air in the other compartment, said partition provided with an opening occupied by the engine whereby the air in moving from one compartment to the other will be directed against the exterior walls of the engine, for the purpose set forth.

4. In an automobile, a multicylinder-engine 55 arranged with its cylinders in a fore-and-aft line, a casing covering the engine, a fore-and-aft partition in the casing dividing it into two compartments, an entrance for air in the front of one compartment and an exit for air in the 60 other compartment, said partition provided with an opening occupied by the engine whereby the air in moving from one compartment to the other will be directed against the exterior walls of the engine, for the purpose set 65 forth.

In witness whereof I subscribe my signature in presence of two witnesses.

JAMES C. ANDERSON.
